UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed November 23, 1923. Serial No. 676,648.

To all whom it may concern:

Be it known that I, ELMER R. POPE, a citizen of the United States, residing at Hamilton, in the county of Essex and Commonwealth of Massachusetts, have invented certain Improvements in Fastening-Inserting Machines, of which the following description, in connection with the accompanying drawing, is a specification, like reference characters on the drawings indicating like parts in the several figures.

My invention relates to machines for inserting nails and similar fastenings, and especially to those for nailing the heel-seats of shoes. In the application in my name bearing the Serial Number 603,576, filed in the United States Patent Office November 27, 1922, is disclosed an apparatus in which close proximity to the rand-crease of the points of insertion of heel-seat-nails is assured by holding each nail in a movable section, which is forced into nailing position by the introduction of the shoe to be operated upon. With each of these movable sections co-operates a reciprocatory driver, completing, with the holding section, a nailing mechanism, each driver being movable independently of the section and brought to the nail-inserting relation by its contact with the corresponding holding section. The object of the present invention is to improve such a structure, particularly with reference to the positioning of the holding sections by the work and the manner of actuation of the drivers.

In the attainment of this object, a feature of the invention consists of a movable support, as a jack for a shoe, toward and from which a fastening-inserting mechanism is movable, together with means, as a spring, for moving the inserting mechanism toward the support, and novel means controlled by the support for opposing the action of the moving means. The thus controlled means is shown as consisting of a weight, normally opposing the action of the spring, but having its effect thereon overcome as the work-support is moved into nailing position, so that the inserting mechanism is at this time carried into engagement with the supported shoe. By this combination, rubbing effect upon the work by its movement along the contacting inserting mechanisms is avoided,

the latter traveling directly against the shoe-upper when it is at rest.

A further feature of the invention involves the holding of the mechanisms against separation from the work during the inserting operation. This is effected by means acting in the movement of a member which actuates the inserting mechanisms, and which prevents movement of said mechanisms. More specifically, a pressure member, movable to depress the drivers which insert the nails, also operates a retaining member for each section of the inserting mechanism, these retaining members being preferably yieldable. Thus, the sections are held firmly in their inserting positions during the driving of the nails.

Another feature of the invention concerns the actuation of the inserting members of the independently movable mechanisms, this being accomplished by an actuating member movable into and out of co-operation with such inserting mechanisms. There are herein illustrated carriers arranged to reciprocate in the sections of the inserting mechanisms, and each having a driver mounted upon it, and a reciprocatory pressure-head movable independently of the carriers and acting upon them to operate the drivers. The independence of movement of the pressure-head, upon the one hand, and the sections with their carriers and drivers, upon the other, produces a capacity of the sections for ready adjustment to the work, to give the proper insertion of the fastenings and a freedom from strain upon the drivers when these are actuated.

A particular embodiment of the invention is illustrated in the accompanying drawings.

Fig. 1 showing a front elevation of the upper portion of a heel-seat-nailing machine in which my improvements are included;

Fig. 2, a side elevation thereof with portions broken away;

Fig. 3, an enlarged broken front elevation of those parts of the apparatus more closely co-operating with the work; and

Fig. 4, a detail in top plan, with a portion in section, showing the die-block and the movable nail-inserting mechanisms mounted thereon.

The general characteristics of the form of

machine which I have chosen to disclose herein may be substantially those of the apparatus of Patent No. 446,885, Pope, February 24, 1891. This includes a frame 10 having separated portions, between which extends a horizontal die-block 12, this furnishing an abutment against the under side of which is pressed the heel-seat of a shoe S which is to be nailed. At the area of contact of the heel-seat with the die-block is shown a recess 14, formed at the bottom of the die-block, this recess serving as a mold, which, as a result of the pressure applied during the nailing operation, imparts to the heel-seat the contour of the concave end of the heel which is to be later attached. The shoe S is carried by a jack 16 mounted to move in ways 17 extending from front to rear of the frame, the ways being at the top of a cross-head 18 arranged to reciprocate vertically in the frame. With the cross-head in its lowered position and the jack drawn out, the shoe to be operated upon may be placed upon said jack, and then pushed in along the ways 17 until it is beneath the die-block. In this position, the machine may be operated to apply pressure to the heel-seat to form it and hold it for the insertion of the nails. Arranged to reciprocate in the frame, at each extremity of the die-block 12, are vertical side rods 19 carrying at their upper extremities a connecting yoke or top girt 20.

The body 22 of the die-block may be formed in sections, to facilitate the assembling with it of the elements which it guides, and is provided with a series of vertical slots 24 extending outwardly from the recess 14, these slots having the relation best illustrated in Fig. 4 of the drawings. In the slots move the body-sections 28 of nail-inserting mechanisms, a section sliding in each slot and being supported by said portions 29 and an end portion 30, which overhang and rest upon the upper surface of the die-block. Upward displacement may be prevented by plates 31 attached to the bottom of the sections. Each section has in its inner, lower portion a holding passage 32, which is preferably inclined downwardly and inwardly, so that the fastenings which these passages contain will be driven toward the interior of the shoe, and not parallel to or in the direction of the counter-portion. By this arrangement, the heel-seat-securing fastenings may be inserted close to the edge of the outsole, to produce a tight rand-crease, without danger of their emerging through the counter-portion of the upper. Nails N are delivered to the holding passages 32 through communicating passages 34 extending from the former in a nearly vertical direction, and to which, at the top of each section 28, is connected a flexible supply-tube 36. The tubes are joined to the discharge device of

a suitable distributing mechanism 38, which may be similar to that which is the subject of Patent No. 663,777, McFeely, December 11, 1900. The flexibility of the tubes 36 permits movement of the sections 28 along the

slots in the die-block, without interfering with the delivery of nails. Alined with each passage 32 is an opening 40, shown as rectangular in transverse section. In this opening is located a carrier-bar 42 arranged to reciprocate longitudinally and having secured to its lower extremity a driver 44. This driver operates in the alined passage 32, contacting, in the movement of the carrier-bar, with a nail in the passage, to drive it into the heel-seat of a shoe held on the jack beneath the die-block. Each bar and driver is normally raised, so that the lower end of the latter is above the nail-delivery passage 34, by a spring 46 located within the opening 40 and situated between the bottom of the bar and a depression in the section 28. Each driver-bar 42 is guided between walls 48, which rise above and extend along the opposite sides of the slots 24. Each section is forced inwardly by a spring 50 held within a bore 52 in the section and abutting at its outer end against a screw-plug 54 threaded through the wall of the die-block at the end of the corresponding slot. The extent of inward movement of each section is gaged by a projection 56 adjustably fixed to the under side of the section by a slot-and-screw connection 58. The inner end of the projection is so formed as to generally correspond to the contour of the counter-portion of a shoe just below the rand-crease, contact of the gaging element at this point furnishing the most accurate location of the nail with respect to the crease. That is, by determining the point of insertion of the fastening by measuring its distance from the point at which it is desired it shall closely approach, this relation is obtainable without

danger of the fastening penetrating the exposed portion of the shoe.

Were it left for the counter-area of the shoe-upper to position the sections by its pressure against the ends of the projections 56 as the jack is moved into nailing position, the rubbing of the upper-material over the projections would be liable to mutilate it. To avoid injury to the stock, the gage-projections are allowed to contact with the work only after it is beneath the die-block. Attached to each section is a wire or other flexible member 60 running over a sheave 62 rotatably mounted upon the plate 31. From the sheave, each wire hangs parallel to the side rods, and opposite groups of these wires carry a rod 64 movable in a bracket 66 depending from the frame. The lower end of each rod is weighted at 68, the magnitude of the total weight of this portion of the system being sufficient to overcome the expan-

sive force of the springs 50, so that the sections 28 are held back with the springs compressed and out of the path of the shoe as the jack 16 is carried into nailing position. 5 Each weight 60 may be further guided and prevented against rotating about the axis of the rod 64 by a curved portion 70 partially embracing the adjacent side rod. Formed upon the under side of each weight 10 is a downwardly and rearwardly inclined surface 72, with which may contact an oppositely inclined surface 74 upon a bracket 76 secured to one side of the base of the jack. With the jack drawn out in the position to 15 receive a shoe, the surface 74 is separated from 72, allowing the weight 78 to exert its effect to hold the nail-inserting sections 28 out and the gaging projections 56 clear of the counter of the shoe when the jack is 20 thrust in. Upon this just-mentioned movement, the surface 74 contacts with 72, elevating the weight and relieving the springs 50 from its effect, so that said springs act to carry the sections 28 toward each other, 25 causing the projections 56 to contact with the counter of the shoe, which at this time has reached its position beneath the die-block and is at rest. Direct contact with the end of the projections, without rubbing action, is thus had, and the ends of the nail-holding passages 32 are presented in the desired relation to the heel-seat. Any excess of movement of the rod 64, under the influence of the surfaces 72 and 74, over that 30 of the gage-projections is compensated for by springs 77 included in the flexible members 60. These springs, naturally elongated under the tension of the weights, contract as the projections are moved in by the springs 52, and thus take up any looseness in the members 60.

The top girt 20 carries, upon its under face, an extension 78, from which depends a series of narrow walls 80 arranged to register with the spaces between the walls 48, so that when the top girt is lowered by the side rods, each wall 80 will strike the upper end of a bar 42, to depress it against its spring 46 and drive the nail in the passage 32. On account of the inclination of the driver-bars 42, their upper ends, as they descend, are shifted inwardly toward the center of the die-block. Contact, however, between the bars and the actuating elements 45 is maintained by the extension of the walls 80 between the abutment-walls 48, there being provided a surface continually contacting with the bar during its entire downward travel. It will be seen that by having the drivers move with the nail-holding sections, and the comparatively massive walls 80 having their operating movement and producing their effect upon the drivers independently of the travel of the sections, and thus 50 unaffected by their positions, the locating of

all the elements of the inserting mechanisms may be accomplished readily, and without throwing harmful strains upon relatively frail parts, as may be the case with the drivers of the machine of the previously-mentioned application. 70

When nails are driven into the heel-seat with an inward inclination, there is a component of the driving force which acts against the springs 50, tending to separate 75 the sections 28 from the work. To guard against this, the top girt and its extension 78 contain a vertical passage 84 lying above each of the overhanging portions 30 of the sections. In each passage 84 operates a retaining member, furnished by a plunger or contact-rod 86, forced down by a spring 88 toward the wall 30. A screw 90 is threaded horizontally into each plunger, and operates in a vertical slot 92 in the top-girt-extension. This limits the downward movement of the plunger under the influence of its spring, so that its lower extremity, when the top girt is raised, is out of contact with the portion 30 of the corresponding inserting section. When, however, the top girt descends and the nails are driven by the action of the walls 80 upon the driver-bars 42, the plungers 86, before the drivers contact with the nails in the passages 32, press upon the portions 30, and thus frictionally retain the sections against outward displacement under the driving pressure. 90

To state briefly the general operation of the machine, it may be said that with the jack 16 drawn out, the operator places a shoe S upon it, and pushes the jack in until the heel-seat of the shoe is vertically alined with the recess 14. Until the shoe has reached this position, the gaging projections 56 are 100 maintained away from it by the weights 68. But when these weights are raised by the jack-surfaces 74, the springs 50 act to carry the sections 28 inwardly, the contact of the projections with the counter-portion of the shoe near the rand-crease correctly locating the ends of the passages 32 over the heel-seat. Now the machine is 105 started in operation, and upon movement of the top girt, the distributor 38 is tripped, so that it delivers a charge of nails N through the tubes 36 and passages 34 into the holding passages 32. In this descent of the top girt, the sections are locked by the frictional engagement of the plungers 86, and then the actuating walls 80 strike the ends of the driver-bars 42, so that the drivers 110 40 are forced down against the nail-heads, inserting the nails in the heel-seat. Upon reverse movement of the top girt, the retaining pressure of the plunger 86 is removed from the inserting sections, and the walls 80 are carried out of contact with the driver-bars. As soon as the outward 115 travel of the jack is initiated, the weights 120 40

68 are released, so that the force of the springs 52 is again effective, and the gag-
ing projections 56 removed from the shoe,
their movement of withdrawal with the sec-
tions continuing without contact with the
upper.

Having described my invention, what I
claim as new and desire to secure by Letters
Patent of the United States is:

- 10 1. In a machine for inserting fastenings, a movable support, a plurality of fastening-inserting mechanisms movable independently of each other and co-operating with the support, yieldable means for moving the inserting mechanisms in such independent movement into position for co-operation with the support, and means exerting a tendency to move the inserting mechanisms in opposition to the moving means.
- 15 2. In a shoe-nailing machine, a movable shoe-support, a nail-inserting mechanism movable toward and from the support, means for moving the inserting mechanism toward the support, and means controlled by the support for opposing the action of the moving means until the inserting position of the mechanism is reached.
- 20 3. In a shoe-nailing machine, a movable shoe-support, a plurality of movable nail-inserting mechanisms co-operating with the support, yieldable means for moving the inserting mechanisms into position for co-operation with the support, means for opposing the action of the moving means, and means for overcoming the effect of the opposing means.
- 25 4. In a shoe-nailing machine, a movable shoe-support, a plurality of movable nail-inserting mechanisms co-operating with the support, means for moving the inserting mechanisms into position for co-operation with the support, means for opposing the action of the moving means, and means for overcoming the effect of the opposing means in predetermined positions of the support.
- 30 5. In a shoe-nailing machine, a movable shoe-support, a plurality of nail-inserting mechanisms movable independently of each other and co-operating with the support, yieldable means for moving the inserting mechanisms into position for co-operation with the support, means for opposing the action of the moving means, and means operable in the movement of the support for overcoming the effect of the opposing means.
- 35 6. In a shoe-nailing machine, a jack movable into and out of nailing position, a movable nail-inserting mechanism, a spring arranged to force the inserting mechanism toward the jack in the nailing position, and means for overcoming the force of the spring until the jack reaches the nailing position.
- 40 7. In a shoe-nailing machine, a jack movable into and out of nailing position, a mov-

able nail-inserting mechanism, a spring ar-
ranged to force the inserting mechanism to-
ward the jack in the nailing position, and a
weight acting upon the inserting means
against the force of the spring.

70

8. In a shoe-nailing machine, a jack mov-
able into and out of nailing position, a mov-
able nail-inserting mechanism, a spring ar-
ranged to force the inserting mechanism to-
ward the jack in the nailing position, a
weight acting upon the inserting means
against the force of the spring, and means
movable by the jack and arranged to relieve
the spring of the effect of the weight.

75

9. In a shoe-nailing machine, a jack mov-
able into and out of nailing position, a mov-
able nail-inserting mechanism, a spring ar-
ranged to force the inserting mechanism to-
ward the jack in the nailing position, and a
weight acting upon the inserting means
against the force of the spring, there being
co-operating surfaces associated with the
weight and jack and arranged to raise the
weight.

80

10. In a fastening-inserting machine, a movable fastening-inserting mechanism, a movable actuating member for the inserting mechanism, and means acting in the movement of the actuating member for preventing movement of the inserting mecha-
nism.

85

11. In a shoe-nailing machine, a movable nail-holder, a reciprocatory driver co-oper-
ating therewith, a pressure member mov-
able to actuate the driver, and a retaining
member for the holder movable under the
influence of the pressure member.

100

12. In a shoe-nailing machine, a plurality of nail-inserting mechanisms including in-
dependently movable sections, a movable ac-
tuating member for the inserting mecha-
nisms, and a retaining member for each sec-
tion carried by the actuating member.

105

13. In a shoe-nailing machine, a plurality of nail-inserting mechanisms including in-
dependently movable sections, a movable ac-
tuating member for the inserting mecha-
nisms, and a yieldable member for each sec-
tion movable upon the actuating member
and carried thereby into contact with such
section.

110

14. In a shoe-nailing machine, a movable shoe-support, a nail-inserting mechanism movable toward and from the support, means for moving the inserting mechanism toward the support into nail-inserting position, and frictional engaging means for retaining the inserting mechanism in such position.

115

15. In a heel-seat-nailing machine, a frame; a group of nail-inserting mechanisms movable thereon independently of each other, rods reciprocating in the frame at each side of the nail-inserting mechanisms, a yoke mounted upon the side rods and ar-

120

65 able into and out of nailing position, a mov-

ranged to actuate the inserting mechanisms, and retaining members yieldable upon the yoke and movable thereby into engagement with the inserting mechanisms.

5 16. In a heel-seat-nailing machine, a frame, a horizontal die-block mounted thereon, a plurality of nail-holding slides movable upon the die-block, drivers reciprocating in the slides, a rod reciprocating vertically in the frame at each side of the die-block, a top girt connecting the side rods and having a portion for actuating the drivers, and plungers movable upon the top girt and contacting with the slides during 10 the actuation of the drivers.

15 17. In a fastening-inserting machine, a plurality of independently movable fastening-inserting mechanisms each including a reciprocatory fastening-inserting member, and an actuating member movable into and out of co-operation with said fastening-inserting members.

20 18. In a shoe-nailing machine, a plurality of independently movable nail-inserting mechanisms, each including a reciprocatory nail-driver, actuating mechanism for moving the drivers, and means independent of the actuating mechanism and exerting a constant tendency to separate the drivers from 25 the work.

30 19. In a shoe-nailing machine, a plurality of independently movable nail-inserting mechanisms, each including a reciprocatory nail-driver and a portion for contact with a shoe to determine the point of insertion of a nail, and a member movable from a point 35 removed from the inserting mechanisms into co-operation therewith and being arranged to actuate the drivers in all positions of the 40 inserting mechanisms.

45 20. In a shoe-nailing machine, a plurality of nail-inserting mechanisms including independently movable sections, a carrier arranged to reciprocate in each section, a driver mounted in each carrier, and a reciprocatory pressure-head movable independently of the carriers and acting upon all of them to actuate the drivers.

21. In a shoe-nailing machine, a plurality of nail-inserting mechanisms including independently movable sections, a carrier arranged to reciprocate in each section, a driver mounted in each carrier, means for holding each carrier with its driver normally separated from the work, and means 50 common to all the carriers and constructed and arranged to impart to the drivers their driving action.

22. In a shoe-nailing machine, a plurality of nail-inserting mechanisms including independently movable sections, a carrier arranged to reciprocate in each section, a driver mounted in each carrier, a spring holding each carrier with its driver normally separated from the work, and a pressure 55 members acting to move the carriers against the force of the springs.

23. In a shoe-nailing machine, a plurality of nail-inserting mechanisms including independently movable sections, a carrier arranged to reciprocate in each section, a driver mounted in each carrier, and a reciprocatory pressure-head normally separated from the carriers but movable into contact therewith.

28 24. In a heel-seat-nailing machine, a frame, a group of nail-inserting mechanisms movable thereon independently of each other, rods reciprocating in the frame at each side of the nail-inserting mechanisms, 60 and a yoke mounted upon the side rods and having a portion movable into and out of engagement with the nail-inserting mechanisms.

33 25. In a heel-seat-nailing machine, a frame, a horizontal die-block mounted thereon, a rod reciprocating in the frame at each side of the die-block a top girt connecting the side rods, a plurality of nail-inserting mechanisms co-operating with the die-block, 65 and a pressure member carried by the top girt and arranged to actuate the inserting mechanisms.

In testimony whereof I have signed my name to this specification.

ELMER R. POPE.
